DESIGN FOR A JAR

Jean Emerit, Paris, France, assignor to the firm
Bonnetti Freres, Seine, France

Application May 31, 1938, Serial No. 77,466

Term of patent 14 years

To all whom it may concern:

Be it known that I, Jean Emerit, a citizen of the Republic of France, residing at Paris, France, have invented a new, original, and ornamental Design for a Jar, of which the following is a specification, reference being had to the accompanying drawing, forming part thereof.

In the drawing

Fig. 1 is a front view of a jar showing my new design;

Fig. 2 is a rear view thereof.

Fig. 3 is a top view.

Fig. 4 is a bottom view.

I claim:

The ornamental design for a jar, as shown.

JEAN EMERIT,

CERTIFICATE OF CORRECTION.

Design No. 110,566.

July 19, 1938.

JEAN EMERIT.

It is hereby certified that the name of the assignee in the above numbered patent was erroneously written and printed as "Bonnelli Freres" whereas said name should have been written and printed as Bonetti Freres, of Seine, France, as shown by record of assignments in this office; and that the said Letters Patent should be read with this correction therein that the same may conform to the record of the case in the Patent Office.

Signed and sealed this 4th day of October, A. D. 1938.

Henry Van Arsdale
